W. SCYZORYK

SMOKER'S STAND ATTACHMENT FOR BEDS

Filed Nov. 11, 1922

Fig. 2.

Inventor:

William Scyzoryk
By Robert J. Doherty

UNITED STATES PATENT OFFICE.

WILLIAM SCYZORYK, OF DETROIT, MICHIGAN.

DESIGN FOR A SMOKER'S STAND ATTACHMENT FOR BEDS.

Application filed November 11, 1922. Serial No. 4,262. Term of patent $3\frac{1}{2}$ years.

To all whom it may concern:

Be it known that I, WILLIAM SCYZORYK, a citizen of the United States, residing at Detroit, in the county of Wayne and State of Michigan, have invented a new, original, and ornamental Design for a Smoker's Stand Attachment for Beds, of which the following is a specification, reference being had to the accompanying drawings, forming part thereof.

er's stand attachment for beds showing my new design, and Fig. 2 is a plan view thereof.

I claim:

The ornamental design for a smoker's stand attachment for beds, as shown.

WILLIAM SCYZORYK.

Witnesses:

ANNA M. DORR,
LEWIS E. FLANDERS.
